UNITED STATES PATENT OFFICE

ARTHUR P. ARMINGTON, OF WILLOUGHBY, OHIO, ASSIGNOR TO THE EUCLID CRANE
AND HOIST COMPANY, OF EUCLID, OHIO, A CORPORATION OF OHIO

SCRAPER DRAFT GEAR

Application filed February 23, 1929. Serial No. 341,999.

This invention relates to draft gears for scrapers or similar earth-moving machines, and particularly to the type of scraper capable while being dragged along the surface 5 of the earth, of scooping a load into the bucket which forms a part of the scraper, transporting the load to the dumping location, and there dumping the same, all of these operations being selectively controlled at 10 the will of the operator.

More particularly my invention embraces the automatic type of draft gear whereby the angularity of the bucket lip as the bucket is loading, is automatically adjusted.

15 Such a draft gear is illustrated and described in detail in my copending application, Serial No. 146,651, filed November 6, 1926, now Patent No. 1,714,118; and the present invention, generally speaking, comprises 20 improvements in the draft gear there set forth; to the end of simplifying and thus cheapening the construction, and at the same time improving the action of the gear.

The exact nature of my invention together 25 with further objects and advantages thereof will be apparent from the following description taken in connection with the accompanying drawings in which Figs. 1 and 2 are views in side elevation showing an example 30 of my invention applied to a scraper, these two figures illustrating the parts shown in two positions to which they may have automatically adjusted themselves, showing the range of bucket adjustment in digging position; Fig. 3 is a detail view likewise in elevation showing the bucket in dumping position; Fig. 4 is a detail plan view as in the horizontal plane, line 4—4, Fig. 2; Fig. 5 is a detail section as in the horizontal plane of line 5—5, 35 Fig. 3; Fig. 6 is a detail partly in section, of the draft eye and immediately associated parts; and Fig. 7 is a detail in elevation showing the manner of connecting my scraper with draft means.

40 With reference now to the drawings the scraper chosen for illustration and specific description of my invention is generally typical of the rotary bucket type commonly known as the "Fresno" type, the bucket 1 of 45 which is generally cylindrical having circu-

lar runners 2 at its ends, the runners being spaced by back and bottom plates 3 and 4 and filled in with end plates 5 whereby a scoop is had capable of rolling on the runners.

Draft is applied to the bucket by the arms 55 6 connected by a transverse tubular member 7 to form a bail or yoke structure, the arms having connection with the bucket by means of studs 8 located concentrically of the runners 2. The yoke structure described also 60 includes a tongue 9 extending forwardly of the member 7 and located centrally thereof.

A transverse rock shaft 10 is carried by the bail and has on its ends arms 11 arranged 65 in the planes of stops 12, 12, extending outwardly of the runners 2. A lever arm 13 extends upwardly of the shaft 10 and has associated therewith a forwardly extending arm 14. A bolt 15 is provided at its lower extremity with means connecting it to the tongue 9 and passes upwardly through an opening in the arm 14. A retainer ring 16 is secured on the bolt 15 and a spring 17 is positioned upon the bolt 15 in compression between the ring 16 and the arm 14, the nuts 70 18 being turned onto the bolt 15 above the arm 14. The adjustment of the nuts 18 is such that the ends of the arms 11 will be maintained by the spring 17 in the paths of the stops 12, 12'. 75

Thus as the bucket is dragged forwardly (to the right, Figs. 1-3) by the yoke or bail its tendency will be to roll (clockwise in these figures). The arms 11, however, are engageable with the stops 12, 12' to prevent such 80 rolling; the stops 12 being shown engaged in Figs. 1 and 2 whereby the bucket is maintained in digging or loading position. After loading of the bucket and transportation of the same to dumping position a forward pull 85 upon the lever arm 13, as by the pull line 19, which may extend to the tractor by which the scraper is drawn, will move the arms 11 against the action of the spring 17, to clear the stops 12 and allow the bucket to roll forwardly. Release of the line 19 allows the spring 17 to immediately return the arms 90 11 to engage the stops 12' (Fig. 3) whereby the bucket is retained in dumping position. After the load is dumped an- 100

other pull upon the line similarly allows the bucket to return to digging position where it is retained by re-engagement of the stops 12.

Pivots connected with the tongue 9 as at 20 are a pair of side members 21 extending forwardly one on either side of the tongue in spaced relation. Secured with the side members 21 as at 22 are a pair of braces 23 having pivotal connection with the bail as at 24, the axes of the connections at 24 and at 20 being aligned.

Thus the side arms 6, the transverse member 7 and the tongue 9 form a primary yoke structure secured with the bucket; while the side members 21 and brace members 23 form a secondary yoke structure having pivotal connection in the line of the joints 20 and 24 with the primary yoke structure; whereby a double yoke structure is had with a joint 20 medial of its length.

Secured between the forward ends of the members 21 is a bracket 25 in which is mounted for movement about the transverse axis 26, a sleeve 27. Slidable in the sleeve 27 is a draft bar 28, the forward extremity of which carries a coupler 40 for connection with draft means as will be described.

Also mounted between the side members 21 for movement about the transverse axis 29 is a bell crank lever 30 having the upwardly, and downwardly and rearwardly extending arms indicated. The upwardly extending arm of the bell crank has connection as at 35 with the clevis 32 on the rearward extremity of the draft bar 28. The downwardly and rearwardly extending arm of the bell crank has connection as by the links 31 with the forward extremity of the tongue 9.

The clevis 32 has an upstanding portion 33 provided with a threaded opening into which is turned a bolt 34. Loosely fitting upon the draft bar 28 between the sleeve 27 and clevis 32 is a sliding bracket 36 having an arm 37 provided with a socket 38 to receive the end of the bolt 34. Positioned about the draft bar, in compression between the members 27 and 36, is a spring 39.

The tendency of the spring 39 is obviously to move the draft bar rearwardly and thus maintain the coupler 40 bearing against the sleeve 27 as in Fig. 2; the tension of the spring and thus the magnitude of such tendency being regulated by the position of the bracket 36 which in turn is controlled by adjusting the bolt 34. For this purpose the bolt 34 is provided at its rearward end with a head 41 carrying a pair of horns 42 between which a bar, stick or similar handy article may be inserted to serve as a lever.

The proportion and arrangement of the parts of the draft gear is such that, as shown in Fig. 2, the yoke structures will be maintained by the spring in straightened relation, with the joint therebetween, and in fact the yoke members and hence the axis of the bell

crank 30, all substantially in the plane of draft between the coupler 40 and the studs 8 of the bucket.

Breaking of the joint downwards from this position is prevented by the abutting relation of the coupler 40 against the sleeve 27.

Suppose, however, that when the bucket is in loading position the bucket lip meets with resistance such as an unusual obstruction or due to completing its load, the resistance being sufficient to overcome the spring 39. The parts will then assume the position of Fig. 1, or of course dependent upon the magnitude of the resistance, a position between those of Figs. 1 and 2. Movement from the position of Fig. 2 will always involve breaking of the joint between the yoke structures upwardly of the straightened relation so that the bucket will tilt rearwardly to elevate its lip over the obstruction or to non-digging position as the case may be. Such tilting of the bucket will also be accompanied by a shortening of the yoke structures which will largely compensate for the overall extension between the coupler 40 and the bucket.

It will be noted that whereas the bell crank connection gives a substantially constant ratio of movement between the draft bar and the tongue 9, the resistance of the spring increases as the parts are moved from the relation of Fig. 2, and likewise the resistance to bending at the joint of the double yoke structure, increases.

The coupler 40 has swivel connection with the draft bar 28, and for the purpose the coupler is recessed as at 43 with a transverse opening. The recess is adapted to receive a collar 44 which is secured with the draft bar as by means of a pin 45. Thus assembly of the coupler onto the draft bar may be had by inserting the collar 44 into the recess 43, inserting the draft bar end within the coupler and collar, and inserting the pin 45 by driving fit through the collar and draft bar, this last operation being had through the transverse opening described. The forward extremity of the coupler 40 is in the form of a clevis having connection with the draft eye 46 by means of a bolt 47, whereby a hinge connection about a horizontal axis is had. The draft eye 46 is adapted for connection with the usual vertically disposed draft pin A of a tractor draw bar B or the like whereby a hinge connection on a vertical axis is had.

Thus the two hinge connections comprise a universal joint, and the coupling means includes both this universal joint and the swivel described, whereby where the scraper is drawn as by tractor over uneven ground, the scraper structure will not be affected by any weaving strains otherwise transmitted through the coupling.

For the purpose of adjusting the position of the lip 48 of the bucket in digging position, I provide a mounting for the shaft 10

capable of adjustment longitudinal of the scraper. To this end I mount the shaft 10 in brackets 49 having portions 50 extending alongside the arms 6 each with an outstanding flange 51. The portions 50 are longitudinally slotted as at 54 and secured each with its arms 6 by a bolt 52. Under the outer head of the bolt 52 is a member 53 having an outstanding flange 55 adjacent the flange 51. A bolt 56 passes through the flanges 51 and 55. Thus tightening of the nut 57 on the bolt 56 draws the bracket 49 rearwardly rotating the bucket counterclockwise, Figs. 1-3, and elevating the lip thereof. After the proper adjustment is made the bolt 52 is tightened.

What I claim is:

1. In a scraper having a bucket and means for controlling the same for effecting loading and unloading thereof, a draft gear comprising a primary yoke structure secured with said bucket, a secondary yoke structure having pivotal connection with said primary yoke structure whereby a double yoke structure is had with a joint medial of its length, one of said yoke structures having a tongue portion extending beyond said joint, the other of said yoke structures having a pair of side members one on either side of said tongue portion, operating means between said side members and extending therebelow and having connection with said tongue portion and movable to control the angular relation of said structures, and means for associating said operating means with draft means whereby said movement thereof will be upward dependent upon draft.

2. In a scraper having a bucket and means for controlling the same for effecting loading and unloading thereof, a draft gear comprising a yoke structure secured with said bucket and having a forwardly extending tongue portion, a secondary structure in pivotal connection with said yoke structure and having a pair of side members, operating means between said side members and extending thereabove and therebelow and having connection with said tongue portion and movable to control the angular relation of said structures, and means for associating said operating means with draft means whereby said movement thereof will be upward dependent upon draft.

3. In a scraper having a bucket and means for controlling the same for effecting loading and unloading thereof, a draft gear comprising a primary yoke structure secured with said bucket, a secondary yoke structure having pivotal connection with said primary yoke structure, a draft bar adapted for draft association with draft means, said draft bar having slidable supporting connection with the forward end of said secondary yoke structure, and operating means supported on one of said yoke structures and associating said draft bar with the other of said yoke struc-

tures, whereby a double yoke structure is had with a joint medial of its length and substantially in the plane of draft, and movable upwardly to shorten said double yoke structure dependent upon draft.

4. In a scraper having a bucket and means for controlling the same for effecting loading and unloading thereof, a draft gear comprising a primary yoke structure secured with said bucket, a secondary yoke structure having pivotal connection with said primary yoke structure, a draft bar adapted for draft association with draft means, said draft bar having slidable supporting connection with the forward end of said secondary yoke structure, operating means supported on one of said yoke structures and associating said draft bar with the other of said yoke structures, whereby a double yoke structure is had with a joint medial of its length and substantially in the plane of draft, and movable upwardly to shorten said double yoke structure dependent upon draft, and spring means mounted on said draft bar and arranged in opposition with said sliding movement and therefore in opposition to said shortening.

5. In a scraper having a bucket and means for controlling the same for effecting loading and unloading thereof, a draft gear comprising a primary yoke structure secured with said bucket, a secondary yoke structure having pivotal connection with said primary yoke structure, a draft bar adapted for draft association with said draft means, a sleeve pivotally mounted on the forward extremity of said secondary yoke structure, said draft bar being slidable in said sleeve, a sliding bracket on said draft bar spaced from said sleeve, a spring on said draft bar between said sleeve and said bracket, operating means supported on one of said yoke structures and associating said draft bar with the other of said yoke structures, whereby a double yoke structure is had with a joint medial of its length and substantially in the plane of draft, and movable upwardly to shorten said double yoke structure dependent upon draft, and means for adjusting said sliding bracket on said draft bar to variably oppose said joint movement.

6. In a scraper having a bucket and means for controlling the same for effecting loading and unloading thereof, a draft gear comprising a primary yoke structure secured with the bucket, a secondary yoke structure having pivotal connection with said primary yoke structure, means adapted to associate the forward end of said secondary yoke structure with draft means for support thereby, whereby a double yoke structure is had, with a joint medial of its length and substantially in the plane of draft whereby as the joint moves upwardly the double yoke structure will be shortened, and means for preventing downward breaking of said joint, and for

causing upward breaking of said joint dependent upon draft, said last-named means including a pivoted lever having its pivotal axis in the horizontal plane of said secondary yoke structure.

5 In testimony whereof I hereby affix my signature.
